UNITED STATES PATENT OFFICE.

FRANK P. ROBERTSON, OF VALMY, NEVADA.

VACUUM-BOTTLE CASE.

Application filed October 30, 1924. Serial No. 746,831.

My invention relates to certain new and useful improvements in vacuum bottle cases and it particularly has for its object to provide means preventing liquid getting down in between the glass bottle and the metal case. Heretofore in vacuum bottles of the type now commonly found on the market, the glass bottle is held within a metallic case by means of a spring cradle that holds the glass bottle from breaking within the container and keeps it spaced from the walls thereof, a rubber gasket being used at the mouth of the container and bottle to make a seal, with a view of preventing liquid working down between the glass bottle and the case. This gasket, however, frequently rots or dries so as to leak with the result that liquid gets down into the case, rots the same and destroys the spring holder for the bottle. Also, in pouring the contents from the bottle this contaminated liquid filters out again and mingles with the contents of the bottle and contaminates the same. It is the primary object of my present invention to provide a structure in which the foregoing objectionable features are fully eliminated.

My invention in its general nature consists in providing the glass bottle with an elastic envelope embedded in a casing or filler of plaster of Paris, or other suitable material, that will fill the space between the metal container and the elastic envelope and effect a permanent seal at the mouth of the glass vessel and that of the container.

In its more detail nature, the invention resides in those novel details of construction, combination and arrangement of parts, all of which will be first fully described, then be specifically pointed out in the appended claims and illustrated in the accompanying drawing, in which:

Figure 1 is a vertical longitudinal section of a vacuum bottle container, the vacuum bottle being shown in elevation, parts of the elastic envelope also being shown in elevation, and other parts in section.

Figure 2 is a horizontal section on the line 2-2 of Figure 1.

In the drawing, in which like numerals indicate like parts in all of the figures, 1 is the glass vessel or vacuum bottle proper which is of the ordinary construction and

4 is the container which also is of the ordinary construction. In carrying out my invention, I provide an elastic envelope 2 for the bottle 1 which preferably does not extend entirely to the mouth of the bottle but leaves the neck of the bottle projecting from the envelope slightly. The envelope 2 may be of any desired thickness of material and manufactured in any desired way, its function being to allow for inequalities in the expansion of the glass of the bottle and that of the filling 3. After supplying the bottle with the envelope 2, it is assembled in its case and plaster of Paris or other suitable filling material is poured in to set and occupy the space between the case 4 and the bottle and the envelope 2 and to form a permanent seal around the mouth of the container and of the bottle. This filler also serves to prevent the bottle being broken by movement within the container. If the bottle should become broken in any way and requires renewal, the plaster of Paris can be broken away and the case used again, if desired.

From the foregoing description, taken in connection with the accompanying drawing, it is thought the complete construction, uses and advantages of my invention will be readily understood by those skilled in the art to which the invention relates.

What I claim is:

1. In vacuum bottles, the combination with the glass bottle proper and the metallic case for containing the same, of an elastic envelope for the bottle and an impervious rigid filler between the envelope and the case said filler embedding permanently the elastic envelope and the glass bottle.

2. In vacuum bottles, the combination with the glass bottle and the metallic case surrounding the same, of an elastic envelope for the bottle and an inelastic filler between the envelope and the case and sealing the space between the case and the mouth of the bottle.

3. In vacuum bottles, the combination with the glass bottle and the metallic case, therefore, of a rubber envelope for the bottle and a plaster of Paris filler occupying the space between the wall of the case and the envelope and bottle.

FRANK P. ROBERTSON.
